William Dean Wallace, Syracuse, N. Y., assignor
to Camillus Cutlery Company, Camillus, N. Y.,
a corporation of New York

Application November 14, 1951, Serial No. 17,376

Term of patent 7 years

(Cl. D22—3)

To all whom it may concern:

Be it known that I, William Dean Wallace, a citizen of the United States, residing at Syracuse, State of New York, have invented a new, original, and ornamental Design for a Knife, of which the following is a specification, reference being had to the accompanying drawing, forming part hereof.

Figure 1 is a side elevational view of a knife, showing my new design;

Figure 2 is a bottom plan view thereof;

Figure 3 is a top plan view thereof;

Figure 4 is an end elevational view thereof, looking at the left end of the knife in Figure 1; and

Figure 5 is an end elevational view thereof looking at the right end of the knife in Figure 1.

I claim:

The ornamental design for a knife, as shown.

WILLIAM DEAN WALLACE.
